Primary Examiner — Eric Goodman*Assistant Examiner* — Christian P McLean*(74) Attorney, Agent, or Firm* — Cantor Colburn LLP**CLAIM**

I claim, the ornamental design for a display screen or portion thereof with graphical user interface, as shown and described.

DESCRIPTION

FIG. 1 is a front view of a display screen or portion thereof with graphical user interface, showing my new design; and, FIG. 2 is another front view thereof, as shown in a display screen environment.

The broken lines are for environmental purposes only and form no part of the claimed design.
